UNITED STATES PATENT OFFICE.

WALTER J. PASINSKI, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

1,391,072.

Specification of Letters Patent. Patented Sept. 20, 1921.

Application filed October 1, 1915. Serial No. 53,591.

To all whom it may concern:

Be it known that I, WALTER J. PASINSKI, a citizen of the United States, residing at Detroit, in the county of Wayne and State of Michigan, have invented certain new and useful Improvements in Adding-Machines, of which the following is a description, reference being had to the accompanying drawings, forming part of this specification.

My present invention relates to adding machines of the general type disclosed in my prior Patent No. 1,023,168 of April 16, 1912, and the Horton Patent No. 1,016,501 of February 6, 1912; and consists mainly in a novel construction, combination and arrangement of parts whereby the length of the "column-actuators" or operating levers of the machine may be materially reduced, and the machine as a whole be correspondingly shortened up, as compared with prior machines of this class, without decreasing the range of movement of such actuators or levers or interfering with the accurate and satisfactory operation of such machines as heretofore constructed. This I accomplish by mounting each of said actuators or levers upon a vertically movable pivot or fulcrum and causing said fulcrum to be depressed with the lever as the latter is rocked upon such fulcrum by the operations of the keys of the machine, as hereinafter described.

In the accompanying drawings, Figure 1 is a vertical section of a machine embodying my invention, showing the operating parts of the machine in elevation; and Fig. 2 a corresponding view with one of the operating keys depressed to its limit of movement. The same letters of reference are used to indicate corresponding parts in both views.

Inasmuch as the general construction and mode of operation of machines of this type is disclosed in the patents heretofore referred to, as well as in various prior patents, the present specification will be confined to a description of the novel features of construction and operation constituting my present invention.

Heretofore, in machines of this class, the column-actuators or operating levers of the machine have usually been pivoted or fulcrumed upon a fixed rod or support at the extreme rear end of the machine, some distance in the rear of the keyboard of the machine, and have extended thence to the forward part of the machine where they co-

operate with the accumulating mechanism. In prior constructions, having the operating levers so mounted, it has been necessary to employ levers of such extreme length, relatively to the length of the machine as a whole, in order to provide the desired range of movement for the front ends of the levers, for their proper coöperation with the operating keys and the accumulating mechanism, and the result has been that the machine as a whole has had to be made of considerably greater length than was necessary for the accommodation of the other mechanisms of the machine. This necessity is entirely overcome by my present invention, which permits the levers in question to be made of approximately the same length as the keyboard of the machine, and the latter to be correspondingly shortened up and reduced in size, as will now be explained.

In the construction disclosed in the drawings, each column-actuator or operating lever A is pivotally supported or fulcrumed at its rear end, at a, upon one arm of a bell-crank lever B which is mounted upon a fixed cross rod C supported in the framework of the machine. Near its forward end the lever A has a slot-and-pin connection, at b, with one arm of a bell-crank lever D which is mounted upon a fixed cross rod E supported in the framework of the machine. The upwardly and forwardly extending arms, B' and D', of the bell-crank levers B and D, are connected by a link or bar F, which in the present instance constitutes a stop-bar for limiting the movements of the parts under the operations of the different keys, as hereinafter described. The forward bell-crank to whose arm D' the front end of the bar F is connected carries the gear-toothed sector or rack G which meshes with the pinion H of the accumulating mechanism, and a coiled spring I connecting the rear end of the lever A and bell-crank B with a cross rod c at the top of the machine serves to yieldingly hold the parts in and return them to their normal position. Each of the levers A is provided with a segmental slot d for the accommodation of the cross-rod C, said rod extending transversely across the machine through the slots d of all of the levers A.

The operating keys J of the machine, which are arranged in the usual denominational rows extending from the front to

rear of the keyboard, are provided immediately above the lever A with laterally extending lugs f which overlie the upper edge of the lever A and serve to depress the latter when the keys are depressed. The reduced lower ends of the keys J are surrounded by coiled resetting springs g confined between the shoulders formed upon the keys at the upper ends of such reduced portions and 10 the horizontal frame-plate h through which the lower ends of the keys pass and in which they are guided.

Under the foregoing construction and arrangement of parts, when any key in any 15 one of the denominational rows of keys is depressed, as in the case of the 5-key in Fig. 2, its lug f will contact with the upper edge of the lever A and depress the front end of the latter, rocking it upon its pivotal 20 support or fulcrum a at its rear end. Such downward movement of the front end of the lever A will be communicated, through the bell-crank D, D', and link or bar F to the bell-crank B, B', with the result that 25 the latter will be rocked upon its fulcrum C and the pivotal support or fulcrum a of the lever A be lowered. The proportions of the parts are such, in the present instance, that such pivotal support or fulcrum of the 30 lever A will be lowered to such an extent, relatively to the depression of the front end of the lever, at the operation of any key, that the lever will be given substantially the same movement as a whole as it 35 would be if it were extended rearward of the keyboard of the machine and supported at its rear end upon a fixed fulcrum or pivot, as in the machines of the prior patents here- 40 tofore referred to. The mountings of the lever A upon a vertically movable support or fulcrum, in the manner described, therefore enables the lever to be very materially shortened, as compared with the necessary length of the levers in the prior construc- 45 tions referred to, while preserving substantially the same movement of the portion of the lever which underlies the keyboard of the machine and is directly acted upon by the operating keys.

50 The depression of the lever A and the rocking of the bell-cranks, in the manner described, will of course put the spring I under increased tension, and when the operated key is released said spring will restore the parts to normal position. The 55 gear-toothed sector G will be reciprocated back and forth at each of such operations, to an extent determined by the particular key operated, and serve to transmit the 60 movement of the parts to the accumulating mechanism, to add the value of the operated key upon it. The accumulating mechanism of the machine may be of any suitable character, that illustrated or indicated in the 65 drawings embodying a ratchet-and-pawl and

gear connection between the pinions II which mesh with the sectors G and the numeral wheels H', under which the latter are advanced at the return movement of the parts in accordance with the values of 70 the operated keys.

So far as the operation above described is concerned, the link or bar F might consist of a simple link connecting the vertical arms of the two bell cranks, but in the present instance it also serves as a stop-bar to positively limit the movements of the parts under the operations of the several keys, to which end it is provided with a series of rearwardly facing shoulders i adapted to co- 80 operate with lugs j projecting laterally from the sides of the key stems slightly below the top plate of the casing of the machine. The adjustment and relation of the parts are such that when any key is depressed to 85 its limit of movement the corresponding shoulder i upon the bar F will, in the rearward movement of said bar, contact with the forward side of the lug j upon the said key, and the latter will act as a stop to arrest the movement of the bar F and the parts connected with it, as in the instance of the depression of the 5-key shown in Fig. 2.

I claim:

1. In a calculating machine, an approxi- 95 mately horizontal column-actuator or lever mounted at one end upon a vertically movable fulcrum, in combination with means for moving said fulcrum simultaneously with movement of the lever upon said ful- 100 crum.

2. In a calculating machine, a column-actuator or lever mounted at one end upon a vertically movable fulcrum, in combination with means for moving said fulcrum 105 vertically when the opposite end of the lever is swung in a vertical plane upon said fulcrum.

3. In a calculating machine, a column-actuator or lever having a vertically movable fulcrum, in combination with means for causing the movement of the lever upon its fulcrum to move said fulcrum vertically. 110

4. In a calculating machine, the combination of a column-actuator or lever fulcrumed 115 at one end upon a vertically movable support, and connections between the opposite end of said lever and said support for causing the latter to be moved vertically when the lever is rocked upon its fulcrum.

5. In a calculating machine, the combination of a column-actuator or lever fulcrumed at one end upon a swinging arm, and connections between the opposite end of said lever and said arm for causing the rocking 125 of the lever upon its fulcrum to swing said arm and lower and raise the fulcrum of the lever.

6. In a calculating machine, the combination of a column-actuator or lever, a bell- 130

crank upon one of whose arms said lever is pivotally supported at one end, and connections between the opposite end of the lever and the other arm of the bell-crank for causing movement of the lever upon its fulcrum to rock said bell-crank and lower and raise said fulcrum.

7. In a calculating machine, the combination of a column-actuator or lever, a bell-crank upon one of whose arms said lever is fulcrumed at one end, a second bell crank at the opposite end of the lever, to one of whose arms the lever is connected, and a link connecting the other two arms of the bell-crank.

8. In a calculating machine, the combination of a column-actuator or lever, a bell-crank upon one of whose arms said lever is fulcrumed at one end, a gear-toothed sector at the opposite end of said lever, and a link connecting said sector with the other arm of the bell-crank.

9. In a calculating machine, the combination of a column-actuator or lever, a bell-crank upon one of whose arms said lever is fulcrumed at one end, a bell crank at the opposite end of said lever, to one of whose arms said lever is connected at said end, a gear-toothed sector carried by said bell crank, and a link connecting the other two arms of the bell cranks.

10. In a calculating machine, the combination, with a denominational row of keys, of a column-actuator or lever extending longitudinally of said row of keys and supported at one end thereof upon a vertically movable fulcrum, and means for causing the depression of any key to rock said lever upon its fulcrum and also depress said fulcrum.

11. In a calculating machine, the combination with a denominational row of keys, of a column-actuator or lever extending longitudinally of said row of keys and mounted at one end thereof upon a vertically movable fulcrum, and means for causing the rocking of said lever upon its fulcrum, at the depression of any key, to depress said fulcrum.

12. In a calculating machine, the combination with a denominational row of keys, of a column-actuator or lever extending longitudinally of said row of keys and mounted at one end thereof upon a vertically movable fulcrum, and a connection between the opposite end of said lever and said fulcrum for causing the rocking of the lever upon its fulcrum, by the depression of any key, to depress said fulcrum.

13. In a calculating machine, the combination with a denominational row of keys, of a column-actuator or lever extending longitudinally of said row of keys, a bell-crank at one end of said row of keys, upon one of whose arms said lever is fulcrumed, and a

connection between the opposite end of said lever and the other arm of said bell crank for causing the rocking of the lever upon its fulcrum, upon the depression of any key, to rock said bell crank and lower the fulcrum of the lever.

14. In a calculating machine, the combination with a denominational row of keys, of a column-actuator or lever extending longitudinally of said row of keys and adapted to be depressed by the depression of any one of said keys, a bell-crank at one end thereof, upon one of whose arms said lever is fulcrumed, a second bell-crank at the opposite end of said lever, to one of whose arms said end of the lever is connected, and a link connecting the other arms of the two bell cranks.

15. In a calculating machine, the combination, with a denominational row of keys, of a column-actuator or lever extending longitudinally of said row of keys and adapted to be depressed by the depression of any one of said keys, a reciprocating bar or link also extending longitudinally of said row of keys, a gear-toothed sector connected with one end of said bar or link for transmitting its movements to an adding mechanism, and a bell-crank supporting the opposite end of said bar or link and so connected with the column-actuator as to cause the depression of the latter to rock the bell-crank and reciprocate the bar or link.

16. In a calculating machine, the combination with a denominational row of keys, of a column-actuator or lever extending longitudinally of said row of keys and adapted to be depressed by the depression of any one of said keys, a reciprocating link or bar also extending longitudinally of the row of keys, a gear-toothed sector connected with one end of said bar and operating to transmit its movements to an adding mechanism, and a bell-crank lever interposed between the opposite end of the bar and the column-actuator and having the end of the bar supported upon its vertical arm and the column-actuator fulcrumed upon its horizontal arm, whereby depression of the column-actuator by the keys serves to rock the bell-crank upon its fulcrum and thereby depress the fulcrum of the column-actuator and also reciprocate the bar connecting the bell-crank with the gear-toothed sector.

17. In a calculating machine, the combination with a denominational row of keys, of a column-actuator or lever extending longitudinally of said row of keys and adapted to be depressed by the depressing of any one of said keys, a reciprocating link or bar also extending longitudinally of the row of keys, a gear-toothed sector connected to one end of said bar and operating to transmit its movement to an adding mechanism, a bell-crank interposed between the opposite end of the

bar and the column-actuator, the bar being supported upon the vertical arm of the bell-crank and the column-actuator being fulcrumed upon its horizontal arm, and a connection between the opposite end of the column-actuator and the reciprocating bar, whereby depression of the column-actuator by the keys serves to rock the bell-crank upon its fulcrum and thereby depress the fulcrum of the column-actuator and also reciprocate the bar connecting the bell-crank with the gear-toothed sector.

18. In a calculating machine, the combination with a denominational row of keys, of a column-actuator or lever extending longitudinally of said row of keys and adapted to be depressed by the depression of any one of them, a reciprocating link or bar also extending longitudinally of the row of keys, a pair of bell-cranks interposed between the opposite ends of the column-actuator and reciprocating bar, the opposite ends of the bar being supported upon the vertical arms of the bell-cranks and the opposite ends of the column-actuator being supported upon the horizontal arms of the bell-cranks, and a gear-toothed sector carried by the forward bell-crank and operating to transmit its movements to an adding mechanism.

19. In a calculating machine, the combination with a denominational row of keys, of a column-actuator or lever extending longitudinally of said row of keys and adapted to be depressed by the depression of any one of said keys, a reciprocating stop-bar also extending longitudinally of said row of keys and provided with a series of stop-shoulders coöperating with the respective keys, a gear-toothed sector connected with one end of the reciprocating stop bar and operating to transmit the movements of the latter to an adding mechanism, and connections between the column-actuator and stop-bar independent of said sector for causing the depression of the column-actuator to reciprocate the stop-bar.

20. In a calculating machine, the combination with a denominational row of keys, of a column-actuator or lever extending longitudinally of said row of keys and adapted to be depressed by the depression of any one of said keys, a reciprocating stop-bar also extending longitudinally of said row of keys and provided with a series of stop-shoulders coöperating with the respective keys, a gear-toothed sector connected with one end of said stop-bar and operating to transmit its movements to an adding mechanism, and a bell-crank supporting the opposite end of said stop-bar and so connected with the column-actuator as to cause the depression of the latter to rock the bell-crank upon its fulcrum and reciprocate the stop-bar.

21. In a calculating machine, the combination with a denominational row of keys, of a

column-actuator or lever extending longitudinally of said row of keys and adapted to be depressed by the depression of any one of said keys, a reciprocating stop-bar also extending longitudinally of said row of keys and provided with a series of stop-shoulders coöperating with the respective keys, a gear-toothed sector connected with one end of said stop-bar and operating to transmit its movements to an adding mechanism, and a pair of bell cranks supporting the opposite ends of the stop-bar and so connected with the column-actuator as to cause the depression of the latter to rock the bell-cranks and reciprocate the stop-bar.

22. In a calculating machine, the combination with a denominational row of keys, of a column-actuator or lever extending longitudinally thereof, a bell crank mounted at one end thereof, upon one of whose arms said lever is fulcrumed at one end, a reciprocating link or bar connected to the other arm of said bell crank, means for causing the depression of any key to rock the lever and bell-crank upon their respective supports, and a series of stop shoulders upon the link or bar coöperating with projections upon the respective keys to limit the movement of the parts under the operations of the different keys.

23. In a calculating machine, the combination with a denominational row of keys, of a column-actuator or lever extending longitudinally thereof and adapted to be depressed by the depression of any one of said keys, a reciprocating stop-bar extending longitudinally of said row of keys and provided with a series of stop-shoulders coöperating with the respective keys, a gear-toothed sector connected with one end of said stop-bar and operating to transmit its movements to an adding mechanism, and a bell-crank interposed between the opposite end of the stop-bar and the column-actuator, the stop-bar being supported by the vertical arm of said bell-crank and the column actuator being fulcrumed upon its horizontal arm, whereby depression of the column-actuator by the keys serves to rock said bell-crank and depress its fulcrum, and also reciprocates the stop-bar and causes the gear-toothed sector to transmit its movements to the adding mechanism.

24. In a calculating machine, the combination with a denominational row of keys, of a column-actuator or lever extending longitudinally thereof and adapted to be depressed by the depression of any key in the row, a bell-crank at one end thereof, upon one of whose arms said lever is fulcrumed at one end, a second bell-crank at the opposite end of said lever, to one of whose arms said lever is connected, a link or bar connecting the other two arms of the bell-cranks, and a series of stop shoulders upon

said bar coöperating with projections upon the keys to limit the movement of the parts under the operations of the different keys.

25. In a calculating machine, the combination with a denominational row of keys, of a column-actuator or lever extending longitudinally of said row of keys and adapted to be depressed by the depression of any one of said keys, a reciprocating stop-bar also extending longitudinally of said row of keys and provided with a series of stop-shoulders coöperating with the respective keys, a pair of bell-crank interposed between the op-

posite ends of the stop-bar and column-actuator, the bar being supported upon the vertical arms of the bell-crank and the column-actuator being supported upon their horizontal arms, and a gear-toothed sector carried by the forward bell-crank and operating to transmit its movements to an adding mechanism. 15 20
